CIGARETTE LIGHTER

David Eberhart, Bound Brook, N.J., assignor to Ronson Corporation, Woodbridge, N.J.

Filed May 20, 1970, Ser. No. 23,094

Term of patent 14 years

Int. Cl. D27—05

U.S. Cl. D48—27

FIG. 1 is a perspective view of a cigarette lighter showing my new design;

FIG. 2 is a top plan view thereof;

FIG. 3 is a side elevational view thereof;

FIG. 4 is a front elevational view thereof;

FIG. 5 is a bottom plan view thereof;

FIG. 6 is a rear elevational view thereof.

I claim:

The ornamental design for a cigarette lighter, substantially as shown and described.
